WELL DRILLING RIG ATTACHMENT

Albert A. Haldeman, Selling, Okla., assignor of
one-half to Ralph E. Gilchrist, Wichita,
Kans.

Application March 28, 1936, Serial No. 71,472

5 Claims. (Cl. 255—19)

This invention relates to well drilling rigs and more particularly to an attachment for said rigs whereby the drilling of a well at an angle to the perpendicular may be readily and easily accomplished.

As is well known because of certain restrictions and other physical inaccessibilities, it is impossible, when drilling in restricted areas to place the derrick and drilling equipment directly over the point of production, and where this is the case it is necessary to drill at an angle to the perpendicular. In accordance with the present invention means is provided for attachment to the drill rig for guiding and supporting the drilling tool in a manner to enable the operator to dig the well at an angle to the perpendicular.

The invention together with its objects and advantages will be best understood from a study of the following description taken in connection with the accompanying drawings wherein:

Figure 1 is a side elevational view illustrating the application of the invention.

Figure 2 is a detail sectional view taken substantially on the line 2—2 of Figure 3.

Figure 3 is an elevational view of one of the sections of a drill string and showing a guide applied thereto.

Figure 4 is an elevational view showing oil sleeves applied to one of the sections of the drill string.

Figure 5 is a sectional view taken substantially on the line 5—5 of Figure 3.

Figure 6 is an elevational view on a small scale illustrating certain parts of the attachment as applied to the well rig.

Figure 7 is an elevational view of a roller equipped member forming part of the invention.

Figure 8 is a view partly in section and partly in elevation illustrating certain details herein-after more fully referred to.

Figure 9 is a view partly in section and partly in elevation showing the application of a roller equipped member to the kelly rod, and

Figure 10 is a detail sectional view taken substantially on the line 10—10 of Figure 9.

Referring to the drawings by reference numerals it will be seen that 5 indicates generally a conventional drill rig which is equipped with suitable cable means 6 for raising and lowering the kelly rod indicated generally by the reference numeral 7. The rod 7 as is conventional operates through the turntable or similar device 8 which forms part of the mechanism for rotating the kelly rod during the drilling operation.

In accordance with the present invention there is provided a trackway comprising a pair of opposed angle iron tracks 9 which are supported at the desired angle to the perpendicular and at one side of the rig 5 through a vertical series of spaced substantially V-shaped brackets 10 the sides of which are secured to the corner post of the rig 5 as at 11.

Each of the members 10 as shown in Figure 8 have secured to opposite sides thereof and extending inwardly from said side bars or arms 12 the inner ends of which are suitably secured to the rails 9. Further the rails 9 and bars 12 are braced with respect to the sides of each member 10 through the medium of brace bars 13.

For connecting the swivel 14 at the upper end of the kelly rod with one end of the cable 6 there is provided a connector which as best shown in Figure 7 consists of a body member 15 provided at its respective opposite ends with hooks 16 and 17, hook 16 engaging in a suitable eye or loop formed in one end of the cable 6, and hook 17 engaging an eye forming part of the swivel 14 as shown in Figure 1.

Projecting from one side of the member 15 are suitable arms 18 the outer ends of which are equipped with pairs of rollers 19 that ride on the rails 9 as shown in Figure 8.

Further in accordance with the present invention the kelly rod 7 intermediate its ends and as shown in Figure 10 is provided with a fixed circular collar 20 that is received within the groove formed in the inner edges of the complementary sections of a two-part clamp 21.

Clamp 21 as shown in Figure 9 has the sections thereof pivotally connected together at one end as at 22 and the free ends of the sections of the clamp are detachably connected together in any suitable manner and as indicated generally at 23.

Projecting radially from one section of the clamp 21 is an arm 24 on the free end of which are suitably mounted rollers 25 which also ride on the tracks 9 as shown in Figure 1.

It will be further appreciated that through the provision of the circular collar 20 and the clamp 21 the clamp and roller assembly as shown in Figure 9 may move with the kelly rod 7 during the raising and lowering of the latter but at the same time rotative movement of the kelly rod 7 and the drill string may be accomplished without any interference on the part of the roller and clamp assembly.

Further in accordance with the present invention to insure the drilling of a straight hole of 55

uniform diameter and thereby prevent bend or "crooks" occurring in the hole during the drilling operation, each section 26 of the drill string, which sections are coupled together in the usual 5 manner and indicated generally at 27 is equipped with a guide device of the type shown in Figure 2.

As illustrated in the preferred embodiment thereof the entire device comprises a sleeve 28 that is sleeved on to a drill string section 26 10 and disposed intermediate of the ends of the section. The sleeve 28 as shown in Figure 4 is externally provided with diagonal oil grooves 29.

Disposed about the sleeve 28 is a substantially cylindrical body member 30 which is of the cross 15 sectional and end elevational shape shown respectively in Figures 2 and 5. The member 30 is clamped on the sleeve 28 through the medium of upper and lower nuts 31 that are threaded on the respective opposite ends of the sleeve 28 20 as shown in Figure 2.

In the upper and lower ends thereof the member 30 is provided with a circular recess, and arranged in each recess is an annular oil retainer 32 of any suitable material held in set 25 position about an adjacent portion of the sleeve 28 through the medium of a corrugated spring 33 as best shown in Figure 5. It will thus be seen that oil from the recesses 31 will be permitted to circulate along the grooves 29 for lubricating 30 purposes.

The member 30 which is made of fiber or other suitable material will fit snugly within the drill hole and serve to maintain the sections of the drill string centered with respect to the hole as 35 it is being bored thus insuring the boring of a straight hole free of any bend or the like.

Further in actual practice it will be apparent that with the rollers 19 and 25 riding along the track 9 disposed at the desired incline or angle 40 relative to the perpendicular the drilling of a hole at an angle to the perpendicular may be efficiently accomplished.

Having thus described the invention, what is claimed as new is:

45 1. In a well drilling apparatus, the combination with a drilling rig, a kelly rod and an operating cable, of a guide structure mounted on one side of the drill rig and including a trackway disposed at an angle to the perpendicular, 50 a member operatively connecting one end of the cable with the kelly rod, said member having arms projecting therefrom and rollers on the ends of the arms riding in said trackway, said kelly rod intermediate its ends being also pro-

vided with a fixed circular collar, a clamp embracing said collar, said clamp having an arm projecting therefrom, and rollers on the free end of said arm operating in said track.

2. For use in drilling bore holes of the class 5 described and at an angle to the perpendicular, a guide structure adapted to be mounted on a well drilling rig, said guide structure including spaced track rails disposed at an angle to the perpendicular, a kelly rod, said kelly rod having 10 a circular collar intermediate its ends, a two-part clamp embracing said collar, said clamp having an arm extending therefrom, and rollers on the free end of said arm ridable along said track rails.

15 3. A well drilling apparatus in combination with a derrick, a guideway having support by the derrick at an inclined angle to the perpendicular axis of the derrick, a tackle mechanism suspended from the derrick, a kelly rod, a swivel 20 head connecting the kelly rod with the tackle mechanism, means mounting the tackle mechanism for reciprocative support on the guideway, a guide clamp for engagingly supporting the kelly rod, means mounting the guide clamp for 25 reciprocative movement in alignment with the tackle mechanism, and means for rotating the kelly rod.

4. A well drilling apparatus in combination with a derrick, a guideway having support by the 30 derrick at an incline to the perpendicular axis of the derrick, a tackle mechanism suspended from the derrick, a kelly rod, a swivel head connecting the kelly rod with the tackle mechanism, means mounting the tackle mechanism for reciprocative support on the guideway, a guide clamp for engagingly supporting the kelly rod, means mounting the guide clamp for reciprocative 35 movement on the guideway, and means for rotating the kelly rod.

40 5. In a well drilling apparatus in combination with a derrick, a guide track, means supporting the guide track on the side of the derrick at an incline to the perpendicular axis of the derrick, a tackle mechanism suspended from the derrick, a kelly rod, a swivel head connecting the tackle mechanism with the kelly rod, a carriage 45 mounted on the guide track and connected with the tackle mechanism, a guide clamp engagingly supporting the kelly rod, a second carriage 50 mounted on the guide track for reciprocatively supporting the guide clamp, and means for rotating the kelly rod.

ALBERT A. HALDEMAN.
